[57] CLAIM

The ornamental design for a tea kettle or similar article, substantially as shown.

DESCRIPTION

FIG. 1 is a top, front and left-side isometric view of the tea kettle or similar article showing my new design; FIG. 2 is a top, front and right-side isometric view thereof, with the cover removed and placed on a side thereof;

FIG. 3 is a bottom and front isometric view thereof, with the cover removed thereof and placed on a side; FIG. 4 is a top plan view thereof, with the handle in a vertical position;

FIG. 5 is a bottom view thereof, with the handle in a vertical position;

FIG. 6 is a right-side elevational view thereof, with the handle in a vertical position;

FIG. 7 is a rear end view thereof, with the handle in a vertical position;

FIG. 8 is a front end view thereof, with the handle in a vertical position; and

FIG. 9 is a left-side elevational view thereof, with the handle in a vertical position.
